CLAIM

The ornamental design for a machine for forming concrete, as shown.

DESCRIPTION

FIG. 1 is a top plan view of a machine for forming concrete showing our new design;

FIG. 2 is a right side elevational view thereof;

FIG. 3 is a left side elevational view thereof;

FIG. 4 is a front elevational view thereof;

FIG. 5 is a rear elevational view thereof; and

FIG. 6 is a top, front and right side perspective view thereof.
